(57) **CLAIM**

The ornamental design for a solar torch light, as shown and described.

DESCRIPTION

FIG. 1 is a perspective view of a solar torch light showing my new design;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The broken lines in the drawings are included for the purpose of illustrating portions of the solar torch light that forms no part of the claimed design.
